UNITED STATES PATENT OFFICE.

GEORGE LEES, OF PHILADELPHIA, PENNSYLVANIA.

IMPROVEMENT IN DEVICES FOR OPENING AND CLOSING FURNACE-DOORS.

Specification forming part of Letters Patent No. 159,190, dated January 26, 1875; application filed December 5, 1874.

To all whom it may concern:

Be it known that I, GEORGE LEES, of Philadelphia, in the county of Philadelphia and State of Pennsylvania, have invented certain new and useful Improvements in Opening and Closing Locomotive-Furnace Doors; and do hereby declare the following to be a full, clear, and exact description of the invention, such as will enable others skilled in the art to which it pertains to make and use it, reference being had to the accompanying drawings, which form part of this specification, in which—

Figure 1 is a perspective of invention; Fig. 2, a perspective of modification of the invention. Fig. 3 is a detail view.

My invention has for its object to provide an arrangement of devices by which a locomotive-furnace door may be readily opened and closed by the application of the fireman's or stoker's foot. My invention consists in the peculiar and novel construction and combination of parts, as hereinafter fully described.

With my improvement, instead of requiring the fireman to lay down his shovel in order to open the door with his hand, he has merely to place his foot upon a treadle conveniently arranged for that purpose. The furnace-door at once fully opens, and remains in that position until the fireman again puts his foot upon the treadle, when the door promptly closes and latches.

In the accompanying drawing illustrating my invention, A represents the front of a locomotive-furnace; B, the foot-board; and C, the door, having a latch, D. E E are hinges, made fast to a pintle-post, F, turning in bearings f, and terminating in a flat end, F', twisted to form a screw or spiral, as shown. G is a lever, fulcrumed at g, and having a slot, g', through which the screw F' passes. By moving the lever G up and down upon its pivot the pintle-post F will be rotated, and the furnace-door C be alternately opened and closed. To move the lever, I provide the following arrangement of devices: H is an arm, turning upon a shaft, h, having a weight, h¹, and a treadle, h². I and K are two arms, moving also independently upon the shaft h. These arms are, respectively, secured to sleeves i and k, from which proceed other short arms, i¹ and k¹. When the

arm I is depressed the arm i¹ will be raised, the arms K and k¹ operating in like manner. When the arm H is made to engage with the arm I the furnace-door will be opened. When, on the contrary, it engages with the arm K said door will be closed. To effect such engagement, I provide a pawl or tripper, L, which is pivoted on the treadle h², and which is formed with shoulders l¹ l². Whichever one of the arms I or K is the most elevated, with that the tripper L will engage. When the furnace-door is closed, the arm I is highest; when opened, the arm K. As soon as the tripper engages with one of the arms I or K its opposite shoulder will move clear of the other arm. M is a pivoted dog engaging with the latch D, and d is an arm made fast to the pintle-post F. When the post F begins to rotate on the elevation of the lever G the arm d strikes the tail-piece m of the dog M, causing the lip m to depress the short arm of the latch and raise the other end d' out of the notch n or n' in the staple N.

The operation of the foregoing devices is as follows: The fireman places his foot on the treadle h², thereby depressing the arm H. The tripper-shoulder l¹ thereupon engages with the arm I, depressing the same, raising the arm i¹, and moving the lever G up on the screw F', turning the pintle-post F, and opening the furnace-door. Simultaneously therewith the end g² of the lever G depresses the arm k¹, and raises the arm K. The fireman withdrawing his foot from the treadle h², the weight h¹ causes said treadle to rise until the tripper L comes above the arm K. When the treadle h² is again depressed the shoulder l² will engage with the arm K, depressing it, raising the end g¹ of the lever G, causing the other end to move down upon the screw F' of the pintle-post, rotating the same, and closing the furnace-door. As the arm K goes down, the arm I ascends, resuming its normal position; and as soon as the fireman's foot is withdrawn from the treadle after closing the furnace-door, the arm H and treadle h² come up in like manner.

To prevent the occurrence of a dead-lock, which would transpire unless provision were made against it, when the arms I and K come in the same horizontal plane, I form said arm I with a projection, i. Now, the tripper-shoulder

der l^1 will ordinarily engage with shoulder i^3 ; but should the two arms I and K get in the same horizontal plane, as they may do if the furnace-door be only partially opened, said tripper-shoulder will engage with the shoulder i^4 , depressing the arm I and the door.

A modification of my invention is shown in Fig. 3, wherein I have substituted for the arms I and K pawls O and P. These pawls are pivoted on a frame, Q, consisting of the cross-piece q and arms g^1 g^2 , the said arm g^1 being extended to form a treadle, R, and said frame Q swinging on the shaft p . S is a weighted T-tripper, whose arms s rest upon tail-pieces of the pawls O and P.

The operation of the modification is substantially the same as that of the principal, and is as follows: The furnace-door being closed, the treadle R is depressed, elevating the frame Q until the pawl O meets and raises the lever G, opening the furnace-door, as already described. The door being opened, the fireman raises his foot from the treadle, when the frame Q resumes its normal position, the pawls O and P being restored to the same plane by the gravity of the tripper S. When the treadle is again depressed the pawl P will move the lever G in the contrary direction, closing the furnace-door, the frame Q, and treadle R, and pawls O and P coming back to their original position.

I have thus described instrumentalities for opening and closing a locomotive-furnace door by means of the fireman's foot; but should the fireman in any case disdain the use of these, the door may be opened and closed in the ordinary manner by hand.

In order to cause the door to remain fully

opened when brought into that position—that is to say, at right angles to the front of the furnace—the pintle-post F above the screw or twist F' or at f^2 is made perfectly flat and straight for a short distance. The effect of this is to cause the slot g^2 in the lever G to operate as a lock upon such pintle-post, preventing it from being turned by the jarring motion of the engine. In order therefore to close the door the lever G must be brought down until the slot g^2 begins to move on the twisted or screw portion F' of the pintle-post before a rotation of the latter can be effected. By making the pintle-post flat and straight in like manner below the twisted portion, the furnace-door will be similarly locked when closed.

What I claim as my invention is—

1. The combination of the furnace-door C, latch D, pintle-post F, having the screw or twist F', lever G, arm d, and dog m, substantially as shown and described.
2. The combination, with lever G, of the arms H, I, and K, and treadle h^2 , constructed and operating in conjunction with the tripper L and arms i and k, substantially as shown and described.
3. The pintle-post F, having a twist or screw, F', and a flattened part, f^2 or f^3 , for preventing the accidental rotation of said post when the furnace-door is opened or closed, substantially as shown and described.

In testimony that I claim the foregoing I have hereunto set my hand.

GEORGE LEES.
